(57) **CLAIM**

The ornamental design for a scanner, as shown and described.

DESCRIPTION

The patent or application file contains at least one drawing executed in color. Copies of this patent or patent application publication with color drawing(s) will be provided by the Office upon request and payment of the necessary fee.

1. Scanner

Fig. 1.1 is a front, top perspective view of a scanner;

Fig. 1.2 is a rear, top perspective view thereof;

Fig. 1.3 is a front elevation view thereof;

Fig. 1.4 is a back elevation view thereof;

Fig. 1.5 is a right side elevation view thereof;

Fig. 1.6 is a left side view thereof; and

Fig. 1.7 is a top plan view thereof.

The broken lines and areas enclosed within broken line depict unclaimed features of the scanner.

The appearance of the underside of the scanner is not claimed and therefore not shown.
